(57) **CLAIM**

The ornamental design for a rimmed platter, as shown and described.

DESCRIPTION

FIG. 1 is a perspective view of a rimmed platter showing our new design;

FIG. 2 is a top plan view thereof;

FIG. 3 is a bottom plan view thereof;

FIG. 4 is a right side elevation thereof, the side opposite being a mirror image;

FIG. 5 is a front elevation thereof; and,

FIG. 6 is a rear elevation thereof.

The broken lines shown in the drawings are for illustrative purposes only and form no part of the claimed design.
